CLAIM

The ornamental design for a robot display screen with graphical user interface as shown and described.

DESCRIPTION

The patent or application file contains at least one drawing executed in color. Copies of this patent or patent application publication with color drawing(s) will be provided by the Office upon request and payment of the necessary fee.

Robot display screen with graphical user interface

Fig. 1.1 is a front view of a robot display screen with graphical user interface showing our new design.

Fig. 1.2 is a partial enlarged view of the screen in Fig. 1.1. The portions colored in green of the robot display screen with graphical user interface form no part of the claimed design.
